STERILIZING DEVICE

Howard I. Morris, Lakewood, Ohio

Application April 13, 1939, Serial No. 267,536

15 Claims. (Cl. 21—2)

This invention relates to the art of sterilization and more particularly to a new and improved method of and apparatus for sterilizing receptacles for dispensing beverages, and the like.

Heretofore, many different practices have been followed in sterilizing receptacles for dispensing beverages, however, due to certain drawbacks peculiar to each, such practices have not proven to be commercially successful. For example, where chemical germicides have been used, it was found that to obtain complete sterilization, the use of an effective solution produced undesirable results from a taste standpoint. In other words, it is difficult to obtain a tasteless and harmless germicidal solution which will effectively sterilize receptacles within a period of time commensurate with commercial practicability. Ultra-violet rays as a sterilizing medium has not proven commercially successful due to the length of time that the receptacle must be subjected to the rays to effect complete sterilization. The use of steam at the required temperature and pressure has proven to be a slow and dangerous practice, moreover, the articles when subjected to the steam for the required period of time become too hot to handle and necessitate a cooling period before they can be used.

By the present invention, there is provided a new and improved method of and apparatus therefor for sterilizing receptacles which overcome the undesirable features of the aforesaid prior practices. Through the use of the method contemplated by the present invention I am able to effect complete sterilization of a receptacle for dispensing beverages within a period of time which is commercially acceptable. The apparatus for carrying out the method insures that the receptacle will be completely sterilized.

Briefly, the method of the present invention includes the steps of projecting a germ destroying medium for example a flame upon a receptacle, bringing said medium into contact with substantially the entire surface area of the receptacle, and maintaining such medium in contact with the surface area of the receptacle during a predetermined period so that complete sterilization may take place.

The apparatus of the present invention for practicing the foregoing method comprises a support for receiving a glass or other receptacle in an inverted position, an annular burner positioned concentric with the open end of the receptacle for inducing a flow of flame about the inner and outer surfaces of the receptacle, and a down-draft tube so disposed as to extend into

the inverted receptacle. The tube is associated with a suction fan or other vacuum producing device and serves to withdraw the air from the region adjacent to the bottom of the receptacle, thereby causing the flame from the burner to flow into the receptacle and contact with the entire inner surface thereof. Time control means operable upon the burner and fan insures that the burner will project a flame against the surface of the receptacle for a predetermined period of time.

In the accompanying drawings which illustrate a preferred embodiment of the invention:

Figure 1 is an elevational view of the sterilizer showing a receptacle thereon in position to be sterilized.

Figure 2 is a vertical sectional view taken on the line 2—2 of Figure 1.

Figure 3 is a horizontal sectional view taken on line 3—3 of Figure 2.

Figure 4 is a vertical sectional view taken on the line 4—4 of Figure 2.

Figure 5 is a wiring diagram.

Figure 6 is an enlarged detail sectional view of the valve controlling the flow of gas to the burner, and

Figure 7 is an enlarged fragmentary sectional view illustrating the flow of flame against the surface of the container.

Referring to the drawings, the sterilizing apparatus is encased in a hollow cabinet 10, which may be constructed in any appropriate manner of any suitable material such as sheets of steel welded, bolted or otherwise secured together and mounted on a base 11. The top 12 of the cabinet 10 is provided with a centrally disposed circular opening 13, spanning which opening are a pair of spaced bars 14, the ends of which are secured to the lower surface of the top 12. The bars 14 serve to support a receptacle A in inverted position above the opening 13 and in position to be sterilized. The interior of the cabinet 10 is divided into a plurality of chambers 15, 16, and 17 by means of spaced plates 18 and 19 secured to the side walls of the cabinet 10 between the top and bottom thereof.

Sterilization of the receptacle A is effected by means of a flame or other germ destroying medium which is directed against the interior and exterior surfaces of the receptacle. This flame is preferably provided by a burner 20 disposed within the chamber 15. The burner 20 preferably takes the form of a hollow annular manifold 21, which is divided by means of plate 55 22 into an upper chamber 23 and a lower cham-

ber 24, communication therebetween being effected by means of spaced openings 25 in the plate 22. The upper surface 26 of the manifold is downwardly and inwardly inclined and provided with a plurality of openings or jets 27. The manifold 21 is preferably divided into an upper and a lower chamber so that an adequate supply of the combustible mixture at a uniform pressure will be present throughout the upper chamber 23 so as to provide a uniform annular flame projecting upwardly from the burner and against the surface of the receptacle A. The combustible mixture is introduced into the lower chamber of the manifold through a vertically disposed mixing tube 28. The chamber 15 is suitably vented to the atmosphere through the openings 29 in the side walls thereof to afford an adequate supply of air at all times within the chamber.

The burner 20 is supported within the chamber 15 in spaced relation with respect to the top 12 of the cabinet by means of supporting plates 30. The inclined face of the burner is positioned concentric with the opening 13 and is of such size that the flame projected therefrom will engage the inner and outer surface of the receptacle.

For bringing the flame projected from the burner into contact with the entire inner surface of the receptacle there is provided a down-take tube 31 which projects upwardly into the receptacle and serves to convey gases from the region adjacent to the bottom of the inside of the receptacle. The down-take tube consists of telescoped tubular members 32 and 33, the latter being supported on the plate 18 in communication with an opening 34 therethrough. Disposed in the chamber 16 in alignment with the opening 34 is a suction fan 35. The chamber 16 is suitably vented to the atmosphere through the openings 36.

The upper end of the tube 32 is provided with prongs 37 which engage the bottom of the receptacle A when the same is disposed thereover. Secured to the tube 32 adjacent to its upper end as at 38 is a perforated cone 39. In the space between the cone 39 and the telescoped tubes 32 and 33 and encircling the latter is a spring 40, the upper end of which is wedged against the inner surface of the cone and the lower end seats on the plate 18. The spring 40 is of sufficient strength only to support tube 32 and cone 39 and to maintain the end thereof against the bottom of a receptacle, the weight of the receptacle being sufficient to overcome the resiliency of the spring and permit the edge of the receptacle to rest on the bars 14. The cone is provided with a flange 41 which can engage the bars 14 and restrict the upward movement of the tube 32.

Gas or other combustible material is conveyed through conduit 42 from a suitable source of supply and passes to the burner 20 through a solenoid controlled valve 43. The valve comprises a cylindrical shell 44 extending through the plates 18 and 19, with one end thereof positioned adjacent the open end of the mixing tube 28 and the other end connecting to the conduit 42. The opposite ends of the cylinder 44 are closed by members 45 and 46 each having a restricted opening extending therethrough. The 70 opening in the member 45 is bevelled as at 47 to receive the conical end of a valve member 48 which is freely movable within the cylinder 44. The valve member 48 is provided with an axially extending bore 49 and a transverse bore 50 inter-

secting therewith. Through the conical end of the valve member 48 the axial bore 49 is vented to the opening through the member 45 by the bore 51. By this construction there is provided a small continuous flow of gas through the valve and into the burner 20, so that a small flame is always present which serves as a pilot flame when the valve is opened. Disposed within the chamber 16 and encircling the cylindrical valve housing 44 is a winding 52, which is adapted to control the position of the magnetic valve member 48 and thereby the flow of gas therethrough into the mixing tube 28. The shell 44 and the members 45 and 46 are formed of a non-magnetic material.

A motor 53 is suitably supported from the lower surface of the plate 19, having one end of its armature shaft 54 extending upwardly through an opening in the plate 19 into the chamber 16. 20 The suction fan 35 is secured to and rotated by that portion of the shaft 54 extending into the chamber 16. On the opposite end of the motor shaft 54 is mounted a worm gear 55 which engages with a worm wheel 56 disposed on one end 25 of a shaft 57 journaled in bearings 58 and 59. The shaft 57 carries a gear 60 which engages a gear wheel 61 mounted on a sleeve 62 which is rotatably mounted on a shaft 63, the latter being supported between the motor 53 and the bracket 30 64. The sleeve 62 also carries a switching member 65 which serves to periodically break electrical circuits across the contacts 66 and 67.

With reference to the wiring diagram shown in Figure 5, current flows from one line of a source of current through conductor 70 to contact 71 of the switch 72 to the contact 73, through conductor 74, across contacts 66, through conductor 75 to one end of the winding of the solenoid coil 52 and from the coil through the conductor 76 to the other line of the source of current supply. The motor 53 is suitably connected across the conductors 75 and 76. Current flows to the solenoid coil 52 and motor 53 through the foregoing circuit during a half revolution of the sleeve 62 which brings the switch arm 65 into position to separate the contacts 66 and break the circuit thereacross. When the contacts are broken, the motor is stopped, solenoid coil de-energized and the valve member 48 shuts off the flow of combustible material to the burner 20. The device is then in position for the succeeding sterilizing operation which can be initiated by throwing the switch 72 and connecting contact 71 thereof with contact 77. In this position of the switch 72 the circuit to the solenoid 52 is from one line of a source of current supply through conductor 70 to contact 71 of switch 72 which is connected with contact 77, through conductor 78 across contacts 67, through conductors 79 and 75 to solenoid 52 and to the other line of the source of current supply through conductor 76.

In using the sterilizing device of the present invention, a receptacle A is inverted over the perforated cone 39. The weight of the receptacle overcomes the spring 40, telescopes the tubes 32 and 33, seats on the bars 14, as illustrated in the drawings. When the receptacle to be sterilized is so positioned, the switch 72 is then closed completing a circuit to the motor 53 and the solenoid 52. When the solenoid is energized the valve member 48 is moved upwardly and gas is projected from the valve into the mixing tube 28.

A flame is produced and projected from the burner 20, as shown in Figure 7, around the in-

ner and outer surfaces of the receptacle. Simultaneously with the projection of the flame the suction fan 35 driven by motor 53 withdraws the air from the bottom of the receptacle A. The withdrawal of gases from the region adjacent the bottom of the receptacle causes the flame to flow into the receptacle and to contact substantially the entire inner surface of the receptacle. The flame is caused to closely engage the inner surface of the receptacle as it passes therealong through the medium of jets of air which project from the openings in the perforated cone 39. The air so provided further serves to effect complete combustion of the gases within the receptacle.

The sterilization of the receptacle continues as above described for a pre-determined period, which period is of sufficient duration to effect complete sterilization of the receptacle. I have found that if the receptacle is subjected to the gas flame for a period of from three to five seconds, complete sterilization is effected. This period is determined by rate of rotation of the sleeve 62 upon which is mounted the switching arm 65. The reduction gearing between the motor shaft 54 and gear wheel 61 being such as to cause half a revolution of the sleeve during the predetermined period. Changes in the gearing may be made to either reduce or lengthen the sterilizing period. At the termination of the sterilizing period, the electrical circuit is broken by the switching arm 65 and the motor 53 and solenoid coil 52 are deenergized.

In place of the timing and control mechanism heretofore described, the motor can be driven continuously, and a timing switch can be placed in the circuit to the solenoid coil 52 to control the solenoid valve only or the timing switch can be made to control the motor and solenoid valve.

Although the device herein illustrated for carrying out my method has been described somewhat in detail, it is to be understood that various rearrangements and modifications of parts may be resorted to without departing from the scope or spirit of the invention as herein claimed.

I claim:

1. A device of the class described for sterilizing receptacles, comprising a support for receiving a receptacle, a burner positioned adjacent the open end of the receptacle for projecting a flame against the inner and outer surfaces of the receptacle, a tubular member adapted to extend into the receptacle and terminate adjacent the closed end thereof, and suction producing means associated with the outer end of said tubular member for withdrawing gases from the region adjacent to the closed end of the receptacle into and through said tubular member.

2. A device of the class described for sterilizing receptacles, comprising a support for receiving a receptacle in inverted position, a ring-like burner spaced below the open end of the receptacle for projecting a flame against the inner and outer surfaces of the receptacle, a telescoping tube consisting of a stationary lower member and a movable upper member, said tube adapted to extend into the receptacle with the free end of the movable member resting against the closed end of the receptacle, and suction producing means associated with the lower end of said tubular member for withdrawing gases from the region adjacent to the closed end of the receptacle through said tube.

3. A device of the class described for steriliz-

ing receptacles, comprising a support for receiving a receptacle in inverted position, a ring-like burner spaced below the open end of the receptacle for projecting a flame against the inner and outer surfaces of the receptacle, a telescoping tube consisting of a stationary lower member and a movable upper member, said tube adapted to extend into the receptacle, means for maintaining the free end of said movable member in engagement with the closed end of the receptacle while the same is disposed on said support, and suction producing means associated with the lower end of said tubular member for withdrawing gases from the region adjacent to

5 the closed end of the receptacle into and through said tube.

4. A device of the class described for sterilizing receptacles, comprising a support for receiving a receptacle, a ring-like burner positioned adjacent the open end of the receptacle for projecting a flame against the inner and outer surfaces of the receptacle, a telescoping tube consisting of a stationary member and a movable member, said tube adapted to extend into the receptacle, means for maintaining the free end of said movable member in engagement with the closed end of the receptacle, suction producing means associated with the outer end of said tubular member for withdrawing gases from the region adjacent to the closed end of the receptacle through said tube, and means associated with said tube for directing air streams toward the inner wall of the receptacle to cause the flame projected into the receptacle to adhere closely to the inner wall surface thereof.

5. A device of the class described for sterilizing receptacles, comprising a support for receiving a receptacle in inverted position, a ring-like burner spaced below the open end of the receptacle for projecting a flame against the inner and outer surfaces of the receptacle, a telescoping tube consisting of a stationary lower member and a movable upper member, said tube adapted to extend into the receptacle, means for maintaining the free end of said movable member in engagement with the closed end of the receptacle while the same is disposed on said support, suction producing means associated with the lower end of said tubular member for withdrawing gases from the region adjacent to the closed end of the receptacle through said tube, and means associated with said tube for directing air streams toward the inner wall of the receptacle to cause the flame projected into the receptacle to adhere closely to the inner wall surface thereof.

6. A device of the class described for sterilizing receptacles, comprising a support for receiving a receptacle in inverted position, a burner spaced below the open end of the receptacle for projecting a flame against the inner and outer surfaces of the receptacle, valve means for controlling the supply of fuel of said burner, a tubular member adapted to extend into the receptacle and terminate adjacent the closed end thereof, suction producing means associated with the lower end of said tubular member for withdrawing gases from the region adjacent to the closed end of the receptacle through said tubular member, and means for simultaneously opening said valve and initiating the operation of said suction producing means.

7. A device of the class described for sterilizing receptacles comprising a support for receiving a receptacle in inverted position, a burner spaced below the open end of the receptacle for project-

75

ing a flame against the inner and outer surfaces of the receptacle, valve means for controlling the supply of fuel to said burner, a tubular member adapted to extend into the receptacle and terminate adjacent the closed end thereof, suction producing means associated with the lower end of said tubular member for withdrawing gases from the region adjacent to the closed end of the receptacle through said tubular member, a timing device, and means actuated by said timing device for controlling said valve means.

8. A device of the class described for sterilizing receptacles, comprising a support for receiving a receptacle in inverted position, a burner spaced below the open end of the receptacle for projecting a flame against the inner and outer surfaces of the receptacle, a tubular member adapted to extend into the receptacle and terminate adjacent the closed end thereof, suction producing means associated with the lower end of said tubular member for withdrawing gases from the region adjacent to the closed end of the receptacle through said tubular member, and means including a perforated member associated with the tubular member to direct air streams toward the inner surface of the receptacle whereby the flame projected into the receptacle is caused to adhere closely to the inner wall surface thereof, as it passes therealong.

9. A device of the class described for sterilizing receptacles, comprising a support for receiving a receptacle in inverted position, a burner spaced below the open end of the receptacle for projecting a flame against the inner and outer surfaces of the receptacle; a tubular member adapted to extend into the receptacle and terminate adjacent the closed end thereof, a perforated member encircling said tubular member, the perforated member and inner wall of the receptacle defining a passageway for the flame projected into the receptacle, and suction producing means for causing a flow of air from the interior of the perforated member, through the said passageway and downwardly through said tubular member, said flow of air serving to maintain said flame closely adherent to the inner wall surface of the receptacle.

10. A device of the class described for sterilizing receptacles comprising a support for receiving a receptacle, a burner positioned adjacent the open end of the receptacle for projecting a flame against the inner and outer surfaces of the receptacle, valve means for controlling the supply of fuel to said burner, means including a tubular member and suction creating means for evacuating the region adjacent the closed end of the receptacle, magnetic means for opening and closing said valve, and means for automatically controlling said magnetic means and said evacuating means.

11. A device of the class described for sterilizing receptacles comprising a support for receiving a receptacle, a ring-like burner positioned adjacent to the open end of the receptacle for projecting a flame against the inner and outer sur-

faces of the receptacle, a perforated member extending into the receptacle, said perforated member cooperating with the inner wall of the receptacle to define a chamber for the flame projected into the receptacle, and means including a tubular member and suction producing means associated therewith for inducing a flow of air from the interior of the perforated member into said chamber and therethrough toward the closed end of the receptacle, said flow of air serving to maintain the flame closely adherent to the inner wall surface of the receptacle.

12. The method of sterilizing a receptacle which includes the steps of placing a receptacle 15 on a support, projecting a flame from a point adjacent the open end of the receptacle onto the inner and outer walls thereof, evacuating the region adjacent the closed end of the receptacle, and inducing a flow of air outwardly from the center of the receptacle toward the inner wall thereof and thence toward the bottom of the receptacle thus causing the projected flame to adhere closely to the inner wall surface as it passes therealong.

13. The method of sterilizing a receptacle which includes the steps of placing a receptacle 20 on a support, projecting a flame from a point adjacent the open end of the receptacle onto the inner and outer walls thereof, evacuating the region adjacent the closed end of the receptacle, inducing a flow of air outwardly from the interior of the receptacle toward the inner wall thereof and thence toward the closed end of the receptacle thus causing the projected flame to adhere 25 closely to the inner wall surface as it passes therealong, and automatically interrupting the projection of the flame after a predetermined interval of time.

14. The method of sterilizing a receptacle 40 which includes the steps of placing a receptacle in inverted position on a support, projecting a ring-like flame from a point below the open end of the receptacle onto the inner and outer walls thereof, evacuating the region adjacent the closed 45 end of the receptacle, and inducing a flow of air outwardly from the center of the receptacle toward the wall thereof and thence toward the bottom of the receptacle thus causing the projected flame to adhere closely to the inner wall surface as it passes therealong.

15. The method of sterilizing a receptacle which includes the steps of placing a receptacle 55 in inverted position on a support, projecting a ring-like flame from a point below the open end of the receptacle onto the inner and outer walls thereof, evacuating the region adjacent the closed end of the receptacle, inducing a flow of air outwardly from the interior of the receptacle toward the inner wall thereof and thence toward the closed end of the receptacle thus causing the projected flame to adhere closely to the inner wall surface as it passes therealong, and automatically interrupting the projection of the flame after a predetermined interval of time.

HOWARD I. MORRIS.
